UNITED STATES PATENT OFFICE.

SYLVENUS D. MOSHER, OF STORM KING, NEW YORK.

DESIGN FOR A SKATE.

SPECIFICATION forming part of Design No. 22,951, dated December 5, 1893.

Application filed October 14, 1893. Serial No. 488,168. Term of patent 7 years.

To all whom it may concern:

Be it known that I, SYLVENUS D. MOSHER, of Storm King, in the county of Dutchess and State of New York, have invented a new and original Design for a Skate, of which the following is a full, clear, and exact description.

Reference is to be had to the accompanying drawings forming a part of this specification, in which similar figures of reference indicate corresponding parts in both the views.

Figure 1 is a side elevation of the skate, showing my design; and Fig. 2 is a plan view of the same.

The leading features of my design are, first the skate having the raised surfaces the outlines of which, when viewed in side elevation, appear above the top of the bed, and secondly, the skate having the elongated blade, the lower line of which curves very gradually upward and merges in the base line of the skate nose.

The blade 10 of the skate is relatively long and its base line is sheering or curved gradually upward in front, as shown at 11, merging in the nose 12 which projects slightly above 25 the bed 13 of the skate. The bed has concave sides 14 and on the bed are the raised surfaces 15 and 16, the outlines of which, when viewed in side elevation, appear above the bed top and when viewed in plan represent 30 elongated oval figures, the raised surfaces being provided centrally with open panel-like figures 17, as shown clearly in Fig. 2.

I claim—

The design for a skate herein shown and 35 described.

SYLVENUS D. MOSHER.
